(57) **CLAIM**

We claim the ornamental design for an air cleaner cover for a motorcycle, as shown and described.

DESCRIPTION

FIG. 1 is a perspective view of an air cleaner cover, embodying aspects of the invention.

FIG. 2 is a right-side view of the air cleaner cover of FIG. 1.

FIG. 3 is a left-side view of the air cleaner cover of FIG. 1.

FIG. 4 is a top view of the air cleaner cover of FIG. 1.

FIG. 5 is a bottom view of the air cleaner cover of FIG. 1.

FIG. 6 is a front view of the air cleaner cover of FIG. 1; and,

FIG. 7 is a rear view of the air cleaner cover of FIG. 1.

The portions of the air cleaner cover shown in broken lines are included for the purpose of illustrating environment and form no part of the claimed design.

1 Claim, 5 Drawing Sheets
